UNITED STATES PATENT OFFICE.

HENRY THOMAS BROOKER, OF SOUTHBEND, ENGLAND.

CIRCUIT-CHANGING SWITCH.

Application filed April 11, 1924. Serial No. 705,920.

To all whom it may concern:

Be it known that I, HENRY THOMAS BROOKER, a subject of the King of Great Britain, residing at Southend, Essex, England, have invented certain new and useful Improvements in Circuit-Changing Switches, of which the following is a specification.

This invention relates to improvements in circuit changing switches or contact makers and being particularly suited to wireless receiving apparatus it will be herein-after described in that application.

To obtain the best result when using more than one pair of receiving telephones with a wireless receiving installation it is necessary to connect the telephones in series. When the telephones are in parallel, the magnitude of the audible signals is not so great as when arranged in series, and when the telephones are of varying resistances, the greater resistance telephones take proportionately more of the current thus lessening the magnitude of the audible signals given by the weaker resistance telephones.

An object of the present invention is to provide a piece of apparatus in the form of a circuit changing switch of the accessory or small switch class, the circuit changing switch according to the present invention being noted for simplicity of construction and possessing manufacturing economies enabling the product to be marketed at a price much below that now charged for circuit changing switches of the accessory or small switch class as distinguished from circuit changing switches designed for heavy power requirements. Thus the present invention is eminently suited as a fitting in a wireless receiving set.

Broadly the invention comprises a circuit changing switch in which a movable terminal co-operates with a fixed terminal, so that by the action of coupling the two terminals together the normal circuit connections are automatically broken and the connections for another circuit are closed, the movable terminal being in the second circuit and the fixed terminal being included in both circuits.

In an exemplar form of the invention the fixed terminals are in the form of a two part terminal having a spring controlled sliding component.

To co-operate with these two part ter-

minals the movable terminals may be plug or pin or spade or equivalent terminals.

The accompanying drawings show by way of example a form of circuit changing switch according to the present invention made up in switchboard form as an accessory for insertion as a component in a wireless receiving set.

Fig. 1 is a wiring diagram shewing two telephones in series circuit. Fig. 2 is a sectional elevation of the switchboard, Fig. 3 a plan and Fig. 4 an under plan thereof. Fig. 5 is a sectional detail view of the fixed terminal, Fig. 6 a plan view, Fig. 7 an elevation thereof. Fig. 8 is a variant form of switchboard, and Fig. 9 a form of terminal disc component for use therewith. Fig. 10 is an under plan view of Fig. 8.

It is to be understood that the switchboard shown by way of example is arranged for four pairs of telephones, but by the provision of more terminals, for example, two additional terminals on each side, eight telephones may be used. The total number used depends on the capacity of the wireless set in use.

Referring to Fig. 1 in this wiring diagram the terminals 1 and 2 are connected to the appropriate parts of the receiving circuit. The terminal 1 is metallically connected by a strip 3 to the outer fixed terminal 4, and the terminal 2 is metallically connected by a strip 5 to the outer fixed terminal 6. The intermediate fixed terminals 7, 8 and 9 are normally metallically connected to each other and to the terminals 4 and 6 respectively by movable blades 10, 11, 12 and 13. The normal circuit when only one pair of telephones are in use is as follows, viz., terminal 1, strip 3, fixed terminal 4, telephone terminal 14, telephone 15, movable telephone terminal 16, fixed terminal 7, blade 11, fixed terminal 8, blade 12, fixed terminal 9, blade 13, fixed terminal 6, strip 5 and terminal 2.

Now assuming it is desired to use two telephones these are placed in series circuit as follows. The terminals 14 and 16 of the telephone 15 remain in contact with the terminals 4 and 7 respectively.

The telephone 17 has one terminal 18 connected to the terminal 7 and one terminal 19 connected to the terminal 8.

In order to get the telephones in series it is necessary to cut out the blade 11, and this

is effected by the terminal 19 when this is inserted in the fixed terminal 8. The series circuit is then from 1 to 2 through 3, 4, 14, 15, 16, 7, 18, 17, 19, 8, 12, 9, 13, 6 and 5.

5 The telephones may be inserted between any cooperating pair of fixed terminals and it is not necessary to start between the terminals 4 and 7 and follow on as described.

10 One form of telephone terminal particularly suited for use with the fixed terminals hereinafter described is of the pin type.

15 Referring to Figs. 2 to 7 inclusive of the accompanying drawings, a switchboard 20 has mounted thereon spring grip terminals 4, 7, 8, 9 and 6. The terminals 4, 7, 8 and 9 are metallically connected by screws 21 to blade pieces 10, 11, 12 and 13 respectively and the terminals 4 and 6 are metallically connected by screws 21 and 21^a respectively 20 to the strips 3 and 5 leading to the terminals 1 and 2 respectively. Each terminal comprises a stationary component 22 and a sliding component 23 the latter being under the influence of a spring 24 tending to keep the 25 sliding component in contact with the stationary component 22. The stationary component 22 has a pair of grooves 25 for partly receiving the movable pin terminals (14 etc.,) of the telephones. 26 is a blind-ended 30 nut, 27 a sleeve, and 28 a base disc.

35 Each of the sliding components 23 of the terminals 7, 8, 9 and 6 bears at the appropriate side on an insulating stud or pin 29, the other end of the stud at the terminal 7 resting on the blade 10. The stud at terminal 8 rests on the blade 11, that at 9 on the blade 12, and the stud at 6 on the blade 13. When only one pair of telephones are in 40 use the terminal 14 thereof is inserted for example as shown between the grip components 22 and 23 of the terminal 4 and the terminal 16 is inserted in like manner at the terminal 7 and the circuit is as hereinbefore described. The insertion of the terminal 16 between the grip components of 45 the terminal 7 will skew or cant over the sliding component 23 and move down the insulating stud 29 a sufficient distance to move the blade 10 away from the contacting screw 21 with which it normally engages and thus break the circuit from 10 to 7, and close the circuit through 15.

50 Now assuming that another pair of telephones 17 is to be used.

55 One terminal 18 of the telephone 14 will be connected for example to the terminal 7 and the other terminal 19 to the terminal 8.

60 The insertion of the terminal 19 between the grip components of the terminal 8, will skew or cant over the sliding component 23 thereof and move down the insulating stud 29 a sufficient distance to move the blade 11 away from its contacting screws 21 so as to close the two pair telephone series circuit, the path of this circuit being as herein-

before set out. On the removal of the terminals 16 and 19 the spring 24 returns the sliding component to normal position and the springiness of the blades 9 and 10 push the insulating studs 29 back and contact is 70 made between the said blades and their co-operating screws.

75 It will be noted that the terminals 4 etc., are common to each circuit, that is to say, whichever circuit is closed, the current passes 78 through these terminals.

80 Fig. 8 is a plan of a circular form of circuit changing switch and Fig. 9 a plan of the fixed disc or washer of the fixed terminal showing the receiving grooves 25 for the pin terminals set angularly to one another, so that on insertion of a pair of telephone terminals between the co-operating fixed terminals, the telephone terminals will be disposed in parallelism. This prevents undue 85 strain between the telephone terminal and the flexible connector connected thereto.

What I claim is:

1. An electric connecting device operating as a circuit changing switch, comprising in combination, a fixed terminal and a movable terminal co-operating therewith, said fixed terminal consisting of two components one having a sliding movement relatively to the other, and an insulating member controlled by said sliding component, the insertion of the movable terminal between the two components of the fixed terminal for the purpose of establishing another circuit connection with said fixed terminal causing the sliding component thereof to move the insulating member so as to break connection between the fixed terminal and a contact piece in the normal circuit. 95

2. An electric connecting device operating as a circuit changing switch comprising in combination, a fixed terminal and a movable terminal co-operating therewith, said fixed terminal consisting of a stationary component and a sliding component, 100 and an insulating member controlled by said sliding component, the insertion of the movable terminal between the stationary component and the sliding component of the fixed terminal for the purpose of establishing another circuit connection with said fixed terminal causing the sliding component thereof to move the insulating member so as to break connection between the fixed terminal and a contact piece in the 105 normal circuit. 110

3. An electric connecting device operating as a circuit changing switch comprising in combination, a fixed terminal and a movable terminal co-operating therewith, 115 said fixed terminal consisting of a stationary component and a sliding component, a spring control therefor, and an insulating member controlled by said sliding component, the insertion of the movable terminal 120

between the stationary component and the sliding component of the fixed terminal for the purpose of establishing another circuit connection with said fixed terminal causing the sliding component thereof to move the insulating member so as to break connection between the fixed terminal and a contact piece in the normal circuit.

4. An electric connecting device operating as a circuit changing switch comprising in combination, a fixed terminal and a movable terminal co-operating therewith, said fixed terminal consisting of a stationary component and a sliding component, means on one of said components for receiv-

ing said movable terminal, and an insulating member controlled by said sliding component, the insertion of the movable terminal between the stationary component and the sliding component of the fixed terminal for the purpose of establishing another circuit connection with said fixed terminal causing the sliding component thereof to move the insulating member so as to break connection between the fixed terminal and a contact piece in the normal circuit.

In testimony whereof, I affix my signature.

HENRY THOMAS BROOKER.
